UNITED STATES PATENT OFFICE.

EDWIN POPE, OF QUEBEC, CANADA.

TELEPHONE SIGNALING APPARATUS.

SPECIFICATION forming part of Letters Patent No. 240,335, dated April 19, 1881.

Application filed April 19, 1880. (Model.)

To all whom it may concern:

Be it known that I, EDWIN POPE, of the city of Quebec, in the county and Province of Quebec, Canada, have invented certain new and useful improved mechanism for calling and telegraphing to and from individual stations on any telephonic or telegraphic circuit; and I do hereby declare that the following is a full, clear, and exact description of the same.

The special object of my invention is to do away with the inconvenience at present existing on telephonic circuits in which, when one station is to be notified, the bells or "ells" of all the others on that circuit are sounded; but it may also be used with great advantage on any telegraphic line, the particular benefit being that by using my mechanism any communication between two stations is strictly private, and not capable of being intercepted at any other station on the line. It may be briefly described as consisting of a compound wheel released by the operator and revolving in unison with the wheels at other stations, so as (at a different point in its circumference for each station in the circuit) to operate the striker, and immediately afterward, through a special lever operated by the armature, to "cut in" the telephone or other instrument, which remains in circuit until a current is sent over the line. The wheel in its revolution announces automatically at the controlling-office the number or other distinguishing-mark of its station.

The above arrangement is slightly modified where a long length of line is to be telegraphed over; but for full comprehension of the invention reference must be had to the annexed drawings, in which—

Figure 1 is a plan of way-station apparatus with the parts in their normal position. Fig. 2 is a plan showing position of parts when the telephone is placed in circuit. Fig. 3 is a detail of the wheel; Fig. 4, a plan of controlling-office apparatus; and Fig. 5, a plan of apparatus for a Morse circuit over long lines.

Similar letters of reference indicate like parts. M M are electro-magnets, of any usual construction, and A the armature, to which is attached, near its pivot-point *a*, a spring-rod, B', carrying the striker or hammer B, B² being the bell, and B³ the knob and pin by which hammer is operated.

K is a key, arranged as shown with relation

to the wheel W, presently to be described, pivoted at *k* to the case inclosing apparatus, and having one end weighted, as shown at K', and the other provided with a pin, K², against which presses the spring S, constructed preferably as shown, and connected to the line. The arm K³ presses against the rabbeted end of the hammer B, and holds the key in the position shown in Fig. 1. This wheel W and the wheel X are mounted on the same spindle, the former being made, as shown, of somewhat greater diameter than the latter, so as to leave a space between X and the raised rim or periphery of W, in which are cut obliquely two openings, (marked, respectively, I and O.) O' is a stop in the space between the wheels, and X' a deep indent in the periphery of the wheel X, the side of this, the stop O', and the edge of the opening O being in one continuous line. The periphery of X is, as shown, formed with ratchet-teeth between the openings O and I. The position of the opening I is varied on the wheel of each station.

W' and W² are pins or projections on the outside of the periphery of W, against one of which, according as a current is on or not, presses the pin A' on the armature to hold the wheel still.

Y and Y' are projections from the periphery of W, which, as the wheel revolves, come in contact with a projection, S', on the spring S, breaking the contact between the spring and key K, and thus interrupting the circuit. The position of the pin Y is altered in each wheel to correspond with the opening I. Z Z are similar projections acting in the same way, but differing in number and arrangement at each station, so as to form a distinguishing letter or signal.

A² is an arm or projection from the armature A, which engages with and moves positively in either direction a cut-off lever, C, this being thereby alternately brought in contact with and removed from an adjustable screw, T, connected with the line and the telephone or other instrument, (shown at E, Fig. 1.) Electrical connection is made through the instrument plates or otherwise between the key K, lever C, and instrument E. The other connections shown are separately insulated.

In addition to the above a spring may be arranged and operated in such a way as not

to interfere with the working of the magnet, and at the same time strengthen the stroke of the bell and make the working of the lever C more certain and operative.

5 The above are the devices comprised in the apparatus for any way-station in the circuit. The corresponding arrangement of the apparatus at the controlling-office will now be described. In this case (see Fig. 4) V is the disk 10 or flat wheel, perforated, as shown, at v v, U being the pin to be inserted into either of these, and U' a fixed pin, which always puts the line to the ground. V' and V² are pins corresponding exactly to the pins W' and W² on the wheel 15 W, and the several apertures v v are at the same distances from these pins as the openings I in the wheels at the several stations from the pins W' and W², so as to make the interruption to the current synchronous. These 20 interruptions are made by placing the pin U in the aperture corresponding to the opening in the wheel of the station to be called.

The operation of my invention is follows: When at any way-station in the circuit it is 25 desired to communicate with the controlling-office the knob B³ is pressed in, bringing the hammer B in contact with the bell B², thus releasing the arm K³, and allowing the weighted end K² of the key to bring its upper part and 30 with it the spring S in close proximity with the periphery of the wheel W. By this means the pin Y' comes in contact with the projection S' on the spring S, disengaging this latter from the pin K² on the key, and the current is 35 thereby momentarily interrupted, thus allowing the whole train of wheels, one at each station, to revolve in unison (by means of clock-work or other suitable mechanism) until the pin A' on the armature of the calling-station 40 comes opposite the opening I in its wheel, when, as the current is again interrupted by the projection Y coming in contact with the projection S', as before, the armature drops, so as to allow the pin A' to drop through the 45 opening I upon the ratchet-teeth of the wheel X, which, as the wheel revolves, give vibratory motion to the armature A and rod B' and sound the call, the projections Z Z causing 50 momentary interruptions to the current, and thus indicating to the central office by their number and grouping which office is calling. The interruptions are received on a relay, bell, sounder, or register in the usual way. Although, as before mentioned, all the wheels of 55 a circuit revolve in unison, no effect is produced by such revolution unless the key K has been dropped and the spring S has been brought in contact with the wheel, which only happens at the calling-station. It will be 60 easily seen that although the wheels revolve in unison at each station the alarm is sounded but by one, and that only that one will be put in circuit, as will be presently explained.

On the wheel W may be placed an additional escapement-pin, to prevent the sounding 65 of false calls by interruptions to the current caused by accidents to the line or batteries.

Where a call is given the armature is dropped to release the escapement and immediately raised again, passing over such extra pin; but if dropped by an accidental interruption to the line the armature remains down and checks the wheel.

On arriving at the end of the ratchet-teeth the armature, either by the spring attached thereto or by its own gravity, falls lower, the pin A' thereon dropping into the indent X', the pin A², as it does so, coming against the lower part of the lever C and separating it from contact with the turn-screw T, thus cutting in or placing in circuit the telephone or telegraphic instrument. The wheel still revolving carries the pin A' from the indent X', along the stop O', and out through the opening O till it comes in contact with and is 85 stopped by the pin W', the armature in this position, however, not acting upon the lever C to bring it into contact with the screw T until a current is let in, when the armature is brought up to the position shown in Fig. 1, 90 the wheel then revolving till the pin W², striking against that A', stops and holds it. The key K is also, by the same movement, restored to the position shown in Fig. 1 by a pin on the wheel W, with the upper face of 95 the key coming in contact. When the wheel is in the position shown the dropping of the key K has no effect, as it does not interrupt the current, contact being still made between the key and the spring S by reason of there 100 being no pin at that point on the wheel W to raise the spring S and break the circuit.

To call any way-station from the connecting-office all that is needed is to place the pin U in that perforation v of the disk V which 105 corresponds in situation to the opening I of the station to be called, and then to release the wheel by a momentary interruption of the battery-current. The wheels then revolve, and the current is again interrupted by the movable 110 pin U, and the action goes on as described.

It will, of course, be understood from the foregoing that as the perforations v v in the disk V at the central or connecting station correspond with the openings I in the peripheries of the wheels of the several way-stations, when the current is interrupted by the movable pin U, placed in any one of such perforations, the armature at the station in which the gap I corresponds with such perforations 115 drops through the armatures of the other stations, then resting on the peripheries of the several wheels, and being drawn up again by the magnets as the current is immediately re-established.

Over long lines and for a Morse circuit, although the signaling apparatus is the same, the arrangement of the other parts will require to be varied, preferably in some such way as that shown in Fig. 5, one current being 120 used for signaling purposes and the other for transmitting messages, and a polarized relay, P R, arranged to work the magnets M with a local battery. When the line is not in use a 125

current—say positive—is put on, which causes the polarized relay to close its local circuit, and the wheels are held at the point W^2 . Any station can then put itself in circuit by depressing the key L K (used instead of the knob B^3) until the bell rings, the distinguishing letter or number of the station being given by the pins in the wheel W acting on the spring S , as before described. The controlling office receives this letter or number on an ordinary relay, and putting in the pin for that office reverses the current for a movement, which starts all the wheels, and then checks them again at the point W' by putting on the negative current and keeping it on until the business is transacted. Where an interruption of the current is made by the controlling office in the direct-working plan a reversal of current is made in this.

20 An indicator may, if desired, be used at each station to show that a call has been given, and the apparatus is in every case inclosed to prevent interference therewith.

What I claim is as follows:

- 25 1. In a telegraphic switch and alarm, an armature in its normal position held up by magnets, and when released at a certain point by the interruption of current to said magnets dropping through the periphery of a revolving wheel or disk into a lower position, whence it is automatically restored to its normal position by the revolution of the disk or wheel, all substantially as herein set forth, and for the purposes described.

2. In a telephone signal-switch, the combination, for cutting an instrument in and out of circuit, of the pivoted lever C , brought in contact with and detached from stop T by magnet M and wheels W and X acting upon and through the armature A . 35

3. The combination of the lever C , magnet M , armature A , and double wheel, with openings in outer rim and indent in inner disk, all as herein set forth, and for the purposes described. 40

4. The combined wheels W and X , with fixed opening O and varied opening I in periphery of former, and ratchet-teeth and indent on latter, all as and for the purposes set forth. 45

5. The combination of the wheel W , with projections on periphery of same, key K , and spring S , all constructed and operating substantially as set forth. 50

6. The combination of the wheel W , key K , spring S , and hammer B , as and for the purposes herein described. 55

7. The disk V , with perforations corresponding to openings I in the wheels W of the several stations in any circuit, and movable pin for interrupting or changing the current, all as herein set forth. 60

EDWIN POPE.
